COMBINATION PUTTER COVER AND
GOLF BALL CLEANEREddy Forst, 26500 Flamingo Ave.,
Hayward, Calif. 94544

Filed Mar. 6, 1967, Ser. No. 6,082

Term of patent 14 years

(Cl. D34—5)

I claim:

The ornamental design for a combination putter cover and golf ball cleaner, substantially as shown.
